UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

CAN-BODY-FORMING MACHINE.

1,419,573.

Specification of Letters Patent. Patented June 13, 1922.

Application filed February 24, 1920. Serial No. 360,819.

To all whom it may concern:

Be it known that I, PETER KRUSE, a citizen of the United States of America, residing in the borough of Brooklyn, county 5 of Kings, and State of New York, have invented certain new and useful Improvements in Can-Body-Forming Machines, of which the following is a specification.

This invention relates to automatic machines for forming can bodies, and provides an automatic machine in which can bodies having different shaped ends, and usually tapered, may be formed, and may be removed from the forming horn without mar- 15 ring, or with a minimum of marring.

The invention further provides a novel combination and arrangement of parts for accomplishing the results referred to, hereinafter more fully set forth, and pointed out 20 in the appended claims.

An embodiment of the invention is illustrated in the accompanying drawings. In said drawings:

Figure 1 illustrates so much of an automatic body maker, incorporating the present invention, as is necessary to illustrate the invention, the figure showing the parts in vertical section.

Fig. 2 is an end elevation of the parts 30 shown in Fig. 1.

Fig. 3 is a view similar to Fig. 1, showing the parts, together with the can body which has been formed thereon, in a different position.

Fig. 4 is a sectional view on the line IV—IV, Fig. 1.

Fig. 5 is a sectional view on the line V—V, Fig. 1.

Figs. 6 and 7 are diagrammatic views.

Fig. 8 is a view showing the operative connections of the feed bar and horn support.

Fig. 9 is a timing chart illustrating the movements of the feed bar and horn.

In said drawings:

Numeral 10 designates a horn, 11 a bracket having a ledge 12 between which and the horn, the body blanks are fed, the bracket 11 conveniently having pivoted thereto wingfolders 14 by means of which the blank is wrapped around the horn.

Numeral 16 designates a bumper for closing the side seam of the body wrapped around the horn, this bumper being moved 55 toward and from the horn in any suitable

manner, as by means of rocking beam 17. Numeral 20 designates the feed table of the machine, the ledge 12 being in prolongation of the feed table 20, and 22 designates suitable feed means for feeding a formed body 60 off the horn and also for feeding off from the horn, or ejecting, the formed body, the feed means conveniently comprising a reciprocating feed bar 22 having feed dogs 23 thereon. Other feed means (not shown) 65 may be provided for feeding the blank on the feed table 20 and onto the ledge 12.

The horn 10 is of the usual expanding type, comprising the sections 24, 25, and the wedge piece 26. An expander slide 27 70 conveniently actuated from the rocking beam 17 through the intermediary of a pin and slot connection 29 actuates the wedge piece 26. The general construction and operation of these horns are set forth in 75 prior patents, for example, 1,234,182, dated July 24th, 1917, 1,129,302, dated February 23rd 1915, both granted to Peter Kruse.

The machine is herein shown as adapted to form a can body which is oval at one end 80 and slightly oblong at the other end, the two ends of the can being of different shape, and the horn 10 is correspondingly shaped; that is it is substantially oval at one end and substantially oblong at the other end. 85 Moreover the can body is here shown as tapered, the horn having a corresponding taper. The can body, however, may or may not be tapered and the particular shapes given are given merely by way of illustration of can bodies having different shaped ends.

In operation, body blanks are fed along the feed table 20, on to the ledge 12 beneath the horn 10, the blanks having been previously edged, (or notched and edged) and when in position between the ledge 12 and horn 10 they are wrapped around the horn by the wings 14, the hooked edges being overlapped, and the horn expanding to 100 bring the hooks on the overlapped edges together. Thereupon the bumper 16, which has been approaching, strikes the can body along the seam formed by the inter-hooked edges, and closes the seam in a well known 105 manner. The expansion of the horn may, as heretofore explained, be effected by the expander slide 27 acted upon by the beam 17 carrying the bumper.

The feed slide 22 thereupon acts to push 110

the body off the horn. The side of the horn adjacent to the ledge 12 is parallel to said ledge, in order that the blank may have a straight line feed, and if the formed blank 5 were slid from the horn in the forming position, it will be seen (especially with reference to Figs. 6 and 7) that the rear end of the body would have its portion which is adjacent to the ledge, squeezed between 10 the front end of the horn and the said ledge, thereby bending out of shape and marring the rear end of the body. In order to avoid this marring of the can body, the horn is lifted, or the horn and ledge are relatively 15 moved, to an extent which will permit the shape or outline of the front end of the horn coinciding to the greatest possible degree with the shape or outline of the rear end of the can body to be ejected. Moreover 20 the lift of the horn is preferably effected in timed relation to the advancing movement of the feed bars and dogs 22, 23, so that the can body is not raised from the ledge 12, and slides along or close to said 25 ledge, whereby the feed dog 23 remains against the rear end of said can body throughout its movement off of the horn. Fig. 6 shows the can body immediately after being formed, and shows the front end 30 of the horn by cross-hatching. Fig. 7 shows the can body as it is leaving the horn, the outline of the front end of the horn being shown in a position coinciding with the outline of the rear end 35 of the can body and being shown by cross-hatching. From these figures and from the foregoing description it will be seen that the can body passes off the horn without being bent or dented. In all cases of can 40 bodies with different shaped ends, the present invention permits of the can bodies passing off of the horn without being dented or with only minimum denting or marring. Where it is possible to avoid denting, this 45 can be effected by the present means.

The lifting of the horn may be effected in any suitable manner. As here shown the horn is fixed to the slide 40. This slide is moved up and down by means of a rock arm 50 41, one end of which has a pin and slot connection 42 with the slide, and the other end of which is connected to an actuating rod 43, having a finger or roller 44 driven by a suitable cam, as indicated at 45. 46 designates a crank-disk which may be used to reciprocate the feed bar 22 through a lever 47 and links 48, 49. The timed relation of the feeding mechanism and of the horn-lifting mechanism may be seen from Fig. 9. 60 The inventive ideas herein set forth may receive other embodiments than that which is specifically illustrated and described.

What I claim is:—

1. A can body forming machine adapted 65 to form bodies with different shaped ends,

comprising a correspondingly shaped horn, a closely adjacent ledge between which and the horn a body blank moves, feed means on said ledge for ejecting a body from said horn, and means acting in timed relation 70 with said feed means for separating said horn and ledge to an extent permitting the rear end of a body formed on the horn to pass over the front end of a horn in a position wherein its outline coincides most 75 nearly with the outline of the front end of said horn, said feeding means and said means for separating the horn and ledge acting simultaneously, whereby said body is not substantially lifted from said ledge during 80 the ejection.

2. A can body forming machine adapted to form bodies with different shaped ends, comprising a correspondingly shaped horn, a closely adjacent ledge between which and the horn a body blank moves, feed means on said ledge for ejecting a body from said horn, and means acting in timed relation 85 with said feed means for separating said horn and ledge to an extent permitting the 90 rear end of a body formed on the horn to pass over the front end of a horn in a position wherein its outline coincides most nearly with the outline of the front end of said horn, said ledge being substantially 95 parallel to the adjacent face of said horn, said feeding means and said means for separating the horn and ledge acting simultaneously, whereby said body is not substantially lifted from said ledge during the 100 ejection.

3. A can body forming machine adapted to form bodies with different shaped ends, comprising a correspondingly shaped horn, a substantially level feed table along which 105 blanks are fed, a closely adjacent ledge between which and the horn a body blank moves, said ledge being substantially parallel to the adjacent face of said horn and being in prolongation of said feed table, feed 110 means on said ledge for ejecting a body from said horn, and means acting in timed relation with said feed means for separating said horn and ledge to an extent where the outline of the rear end of said horn most 115 nearly coincides with the outline of the front end of said horn previous to the lifting of the horn, said feeding means and said means for separating the horn and ledge acting simultaneously, whereby said 120 body is not substantially lifted from said ledge during the ejection.

4. A can body forming machine adapted to form tapered bodies with different shaped ends, comprising a correspondingly shaped 125 horn, a substantially level feed table along which blanks are fed, a closely adjacent ledge between which and the horn a body blank moves, said ledge being substantially parallel to the adjacent face of said horn 130

and being in prolongation of said feed table, feed means on said ledge for ejecting a body from said horn, and means acting in timed relation with said feed means for 5 separating said horn and ledge to an extent where the outline of the rear end of said horn most nearly coincides with the outline of the front end of said horn previous to the lifting of the horn, said feeding means 10 and said means for separating the horn and ledge acting simultaneously, whereby said body is not substantially lifted from said ledge during the ejection.

5. A can body forming machine adapted 15 to form bodies with different shaped ends, one end being substantially oval and the other end being substantially rectangular, comprising a correspondingly shaped horn, a closely adjacent ledge between which and 20 the horn a body blank moves, feed means

on said ledge for ejecting a body from said horn, and means acting in timed relation with said feed means for separating said horn and ledge to an extent permitting the rear end of a body formed on the horn to 25 pass over the front end of a horn in a position wherein its outline coincides most nearly with the outline of the front end of said horn, said feeding means and said means for separating the horn and ledge 30 acting simultaneously, whereby said body is not substantially lifted from said ledge during the ejection.

In witness whereof, I have hereunto signed my name in the presence of two sub- 35 scribing witnesses.

PETER KRUSE.
